US0D1059208S

(12) **United States Design Patent** (10) Patent No.: **US D1,059,208 S**
(45) Date of Patent: ** Jan. 28, 2025

(54) **INDOOR CULTIVATION APPARATUS**

(71) Applicant: **Shrooly LTD**, London (GB)

(72) Inventors: **Sámuel Schaffhauser**, Lókút (HU);
Dávid Palánki, Hegyesh (HU)

(**) Term: **15 Years**

(21) Appl. No.: **35/518,737**

(22) Filed: **Sep. 21, 2023**

(80) **Hague Agreement Data**

Int. Filing Date: **Sep. 21, 2023**

Int. Reg. No.: **DM/232252**

Int. Reg. Date: **Sep. 21, 2023**

Int. Reg. Pub. Date: **Oct. 20, 2023**

(51) **LOC (15) Cl.** **11-02**

(52) **U.S. Cl.**

USPC **D11/144**

(58) **Field of Classification Search**

USPC D11/144, 155, 145; 47/1.1; D26/55;

D30/104

CPC A01G 31/02; A01G 9/247

See application file for complete search history.

Primary Examiner — Brett Miller

(57) **CLAIM**

The ornamental design for an indoor cultivation apparatus as shown and described.

DESCRIPTION

1.1 : Front

1.2 : Back

1.3 : Bottom

1.4 : Top

1.5 : Left

1.6 : Right

1.7 : Perspective

The design is a smart electronic device that automatically grows mushrooms in a few days including rare mushroom species.

1 Claim, 7 Drawing Sheets
